UNITED STATES PATENT OFFICE.

JOHN H. BARRETT, OF NEW YORK, N. Y.

STATIONARY-WASHTUB COVER-HOLDING DEVICE.

Application filed December 18, 1926. Serial No. 155,701.

This invention relates to retaining devices and has particular reference to a holder for retaining the covers of stationary washtubs in an elevated or raised position and against 5 accidental closing while the tub is in use.

The invention comprehends a simple, efficient and inexpensive device of this character in the nature of a flexible element anchored at one end to the wall above the 10 washtub and provided with a hooked member carried at the free end of the flexible member for engagement with the free edge of the tub cover.

With the above recited and other objects 15 in view, reference is had to the following specification and accompanying drawings in which there is exhibited certain examples of embodiments of the invention which are in no way intended as limitations upon the 20 scope of the appended claims as it is to be clearly understood that variations and modifications which properly fall within the scope of said claims may be resorted to when found expedient.

25 In the drawings—

Figure 1 is a perspective view illustrating a double stationary washtub with one of the covers elevated and retained by the device in elevated position and with the 30 other device inactive;

Fig. 2 is a face view of the device;

Fig. 3 is an edge view thereof;

Fig. 4 is a face view of a modified form of hooked member;

35 Fig. 5 is a sectional view thereof;

Fig. 6 is a fragmentary perspective view illustrating the use of the modified form.

Referring to the drawings by characters of reference, 10 designates a washtub cover which in the usual construction is provided with a marginal depending flange 11. The retaining device includes a flexible element 12, such as a chain, which is provided at one end with an anchoring device 13, such as a screw eye, which is screwed into the wall above the washtub. The opposite end of the chain or flexible element 12 has connected therewith a hooked member 14, which is preferably in the nature of a strip of sheet metal, riveted or otherwise connected at 15 to the chain extremity 12, at one of the ends of the strip. The opposite end is provided with a substantially right-angularly bent portion 16 having a reversely bent terminal

17 which overlies, is spaced from, and disposed parallel to the main body of the member. The member 14 is comparatively wide so that it will engage over a substantial area of the flange which is embraced by the portions 16 and 17 so as to prevent accidental 55 displacement in event of a slack being produced in the chain or flexible element 12 should the cover be moved upwardly from its supported position by the device.

In the modified form of the invention illustrated in Figs. 4, 5 and 6, the hooked member 18 is preferably wider and is cut, bent and formed to provide a right-angularly disposed end portion 19 having laterally spaced reversely projecting ears 20—20 60 arranged parallel to and spaced from the main body of the member 18. The hooked member in this form is carried by a flexible element 21 and is especially designed to engage with and retain either one or both of 70 the marginal flanges 22 of the covers 23 of adjacent tubs, as illustrated in Fig. 6.

What is claimed is:

1. A device for holding a flanged washtub cover in open elevated position, comprising a flexible element anchored at one end to the wall above the washtub, and a hooked member carried by the free end of the flexible element and embracingly engageable with the flange at the outer free 80 edge of the washtub cover, said hooked member consisting of a relatively wide element having a right-angularly bent end portion and a reversely bent terminal overlying, spaced from and parallel to the body of the 85 member to embracingly engage the flange over a substantially wide area.

2. A device for holding the flanged metal covers of a pair of adjacent washtubs in elevated open position, comprising a flexible 95 element anchored at one end to the wall above the washtubs and at a point on a line between the same, and a member carried by the free end of the flexible element constructed of sheet material, cut, bent and 100 formed to provide a body portion having a right-angularly bent free end formed with laterally spaced rearwardly directed ears parallel to and spaced from the body portion to constitute hooks for embracingly engaging 105 the flange on the covers.

JOHN H. BARRETT.
